[57] CLAIM

The ornamental design for a front panel for a car heater and air conditioner control unit, as shown and described.

DESCRIPTION

FIG. 1 is a view in perspective of a front panel for a car heater and air conditioner control unit showing my new design;

FIG. 2 is a front elevational view thereof;

FIG. 3 is a left-side elevational view thereof;

FIG. 4 is a front plan view thereof; and,

FIG. 5 is a bottom plan view thereof.

The right-side view is identical to the left-side view shown in FIG. 3. The rear of the front panel for a car heater and air conditioner control unit is not visible in use thereof.

The broken line showing of environmental structure in FIGS. 1-5 is for illustrative purposes only and forms no part of the claimed design.

The cross-hatching in FIGS. 3-5 represents a knurled surface and is understood to extend throughout the areas represented.
